UNITED STATES PATENT OFFICE

172,942

HYDRAULIC HAND PUMP UNIT

William W. Allis, Milwaukee, Wis.

Application February 1, 1954, Serial No. 28,767

Term of patent 14 years

(Cl. D65—1)

To all whom it may concern:

Be it known that I, William W. Allis, a citizen of the United States, residing at Milwaukee, in the county of Milwaukee and State of Wisconsin, have invented a new, original, and ornamental Design for a Hydraulic Hand Pump Unit, of which the following is a specification, reference being had to the accompanying drawings, forming a part thereof.

Figure 1 is a perspective view of a hydraulic hand pump unit, showing my new design;

Figure 2 is a plan view thereof; and
Figure 3 is a side view of the pump.

I claim:

The ornamental design for a hydraulic hand pump unit, as shown.
